UNITED STATES PATENT OFFICE.

ALPHONS H. GITS, OF CHICAGO, ILLINOIS; VALENTINE GITS FARROW ADMINISTRATRIX OF ALPHONS H. GITS, DECEASED.

LUBRICATING DEVICE.

Application filed January 17, 1923. Serial No. 613,298.

To all whom it may concern:

Be it known that I, ALPHONS H. GITS, a citizen of the United States, residing at Chicago, in the county of Cook, State of Illinois, have invented certain new and useful Improvements in Lubricating Devices; and I do hereby declare the following to be a full, clear, and exact description of the invention, such as will enable others skilled in the art to which it appertains to make and use the same.

This invention relates to new and useful improvements in lubricating devices and particularly to shaft lubricating devices of the wick-feed type.

One object of the invention is to provide a lubricator by means of which all of the oil is delivered from the container regardless of the wear on the service end of the wick.

Another object is to provide a lubricator of this character wherein it is unnecessary to renew the entire oil feeding wick as a result of wear at the service end.

Another object is to provide an oil cup of the type mentioned wherein it will be unnecessary to remove the cup for refilling.

In the drawing:

Figure 1 is a vertical sectional view through a steering knuckle of an automobile, and through the oil cup of the invention.

Figure 2 is a view of the wicks, the main portions thereof being broken away.

Referring particularly to the accompanying drawing in which it has been elected to illustrate the invention as used in connection with the steering knuckle of an automobile, 10 represents a portion of one of the stub axles of an automobile, and 11 the vertical spindle or shaft.

In one side of the stub axle 10 there is formed a transverse opening 13, leading into the longitudinal bore 14, of the axle 10, and being internally threaded to receive the externally threaded nipple 15, carried by the upper end of the side of the oil cup or container 16. The upper end of the oil cup 16 is provided with a spring closed cover 17. In the end of the nipple 15, adjacent the side of the cup 16 there is formed a circumferential shoulder 18, which defines the opening 19, leading into the interior of the cup.

A wick, designated as a whole by the numeral 20, has its horizontal portion 21

disposed through the opening 19 and longitudinally in the nipple 15, and its vertical portion 22 disposed in the cup 16. The inner end of the portion 22 is formed with a loop 24 which engages with a similar loop 25, formed on the upper end of the portion 22, whereby a flexible joint is produced which permits the vertical portion 22 to remain in its vertical position in the cup, while the horizontal portion slides within the nipple. The outer end of the portion 21 is disposed a short distance inwardly of the outer end of the nipple 16, and adjacent the opening 13 of the stub axle. Disposed in the bore of the nipple, in encircling relation to the adjacent end portion of the wick, is a coil spring 26 one end of said spring being secured to the adjacent end of the wick and the other end of the spring having bearing upon the shoulder 18. In the end of the nipple there is disposed a cylindrical felt member 27, the outer end of which bears against the spindle 11, to supply oil thereto. The inner end of the felt member is formed with a socket 28 to receive the adjacent end of the wick 20, and is urged against the spindle by the wick 20 under the influence of the spring.

Oil will be drawn upwardly through the wick 20, by capillary action, and be delivered into the bore of the nipple, from whence it will be absorbed by the felt member 27, and finally distributed onto the spindle 11.

When the parts are first assembled, the length of the felt member 27 is such that the spring 26 is compressed within the nipple, and as the outer or service end of the felt member wears away, this spring will advance the felt member to maintain contact thereof with the spindle. Attention is called to the fact that as the felt member advances, the wick 20 moves bodily across the oil cup, the lower end of said wick maintaining its contact with the bottom of the cup so that all of the oil will be drawn from the cup, no matter to what stage of wear the felt member has reached. Thus oil will be delivered from the cup, to the last drop.

It will be noted that with this type of lubricator, the cup does not need to be removed for the purpose of refilling.

Again, when the service end of the wick wears completely away, it is not necessary

to remove the main wick, but simply requires the removal of the cup from the axle, and the replacement of the worn felt member 27, by a new one.

3. By reason of the wire core of the main wick 20, said wick is maintained in the same position or shape, at all times, so that when the new member 27 is pressed into the nipple, the wick will not crowd around the shoulder, as would be the case were an ordinary flexible wick used.

Furthermore, were the felt member 27 not used, the wire core of the wick would contact with the article to be lubricated.

15. While I have shown a wick having a wire core, I wish it understood that a one-piece, felt, or fabric wick may be used with equal facility and effectiveness.

What is claimed is:

20. 1. A lubricating device including a lubricant container, a pair of wicks within the container having their adjacent ends loosely connected, an independent and separable lubricating element carried by one of the wicks, and means for urging the same against an element to be lubricated.

30. 2. A lubricating device including a lubricant container, a pair of wicks within the container having their adjacent ends loosely connected, and an independent and separable lubricating element carried by one of the wicks.

35. 3. The combination with an oil-cup having a laterally directed nipple provided with a shoulder at its inner end, of a wick having one portion disposed vertically in the cup and its other portion flexibly connected with the vertical portion and disposed horizontally within the nipple, a second wick in the nipple and bearing against the adjacent end of the said horizontal portion, and a spring within the nipple and connected with the horizontal portion and bearing against the said shoulder to urge 40 the second wick against a part to be lubricated and simultaneously and bodily move the vertical portion transversely within the cup.

45. 4. The combination with an oil-cup having a laterally directed nipple, of a wick comprising flexibly connected legs, one of the legs being disposed horizontally within the said nipple, the other of the legs being disposed vertically within the cup, a second

wick in the nipple in position to bear 55 against a part to be lubricated, and means within the nipple, for simultaneously urging the second wick against the part to be lubricated and bodily moving the vertical portion of the first wick transversely of the 60 cup to maintain the lower end of the vertical leg of the first wick in constant close proximity to the bottom of the cup.

5. The combination with an oil-cup having a laterally directed nipple, of a spring 65 urged wick having flexibly connected legs, one of which is disposed horizontally in the nipple and the other vertically within the cup, and a replaceable service end for the horizontal leg comprising a felt body provided with a socket receiving the adjacent 70 end of said leg.

6. In a lubricating device, the combination with a lubricant container having a laterally directed nipple, of a pair of flexibly connected wicks, one of which is disposed within the container, while the other is arranged within the nipple, and an independent and replaceable lubricating element 75 carried by the wick within the nipple. 80

7. A lubricating device comprising a cup having a lateral outlet duct, a wire cored wick disposed horizontally within the duct and having an end within the cup bent upon itself to form an eye, a second wire cored wick loosely connected with said eye and depending vertically within the cup, and a spring mounted within the outlet duct and connected with the horizontal wick to cause longitudinal movement thereof, and transverse bodily movement of the vertical wick within the cup. 85 90

8. In a lubricating device, the combination with a lubricant container having a laterally directed nipple provided with a shoulder at its inner end, of a pair of wicks having their adjacent ends loosely connected, one wick being positioned within the container and the other being positioned within the nipple, a replaceable lubricating element 100 carried by the wick within the nipple, and spring means within the nipple and bearing at one end against the shoulder, for urging the replaceable element against an element to be lubricated. 105

In testimony whereof, I affix my signature.

ALPHONS H. GITS.
